INVENTOR.

UNITED STATES PATENT OFFICE.

MILTON TIBBETTS, OF DETROIT, MICHIGAN, ASSIGNOR TO PACKARD MOTOR CAR COMPANY, OF DETROIT, MICHIGAN, A CORPORATION OF MICHIGAN.

INTERNAL-COMBUSTION ENGINE.

Application filed January 7, 1922. Serial No. 527,535.

To all whom it may concern:

Be it known that I, MILTON TIBBETTS, a citizen of the United States, and resident of Detroit, Wayne County, State of Michigan,

5 have invented certain new and useful Improvements in Internal-Combustion Engines, of which the following is a specification.

This invention relates to internal combustion engines and particularly to means for controlling the mixture supplied thereto.

In connection with internal combustion engines, particularly as used in motor vehicles, it is found desirable in starting to 15 increase the richness of the mixture supplied to the engine, and particularly is this true in cold weather. At some times it is even necessary to choke off practically all of the air from the carburetor to permit 20 raw gasoline to enter the cylinders or to be supplied to the intake pipe for producing a very rich mixture to get the initial explosion.

Various forms and types of carburetors 25 have been designed for producing this richness of mixture for starting purposes. In some of them the gasoline nozzle is enlarged or the level is changed and in some the air valves are closed or the air valve 30 springs have their tension increased, and in some cases both of these things are done. In many such carburetors the air is practically all choked off for producing an unusual pull on the gasoline as the engine is 35 turned over by its starting motor.

All such carburetors have a normal or most desirable setting of these various valves and other devices and the parts are designed to be returned to their normal positions as soon as the motor warms up sufficiently to accept and operate upon the leaner mixture which the normal setting produces. Usually the return to normal setting is obtained by manual operation of 40 the control device though in some instances the parts have been automatically returned by the use of thermostats or similar devices.

The present invention has for its salient object the provision of means for returning 45 the carburetor to its normal setting in substantial accord with the warming up of the motor while at the same time permitting manual operation of the controls.

Another object of the invention is to provide means for returning the carburetor to

its normal setting in accordance with the heating up of the motor, but at all events returning the carburetor to its original setting whether the motor heats up or not.

Other objects of the invention will appear from the following description taken in connection with the drawings, which form a part of this specification, and in which:

Fig. 1 is a side elevation of a portion of an internal combustion engine with the present invention arranged thereon, and with parts of the carburetor and control devices in section;

Fig. 2 is somewhat similar to Fig. 1 with the parts in abnormal position;

Fig. 3 is an enlarged plan view of part of the control mechanism shown in Figs. 1 and 2;

Fig. 4 is an enlarged detail view of the spring return device and dash pot, the latter being shown in section;

Fig. 5 is a sectional view of the dash pot with the parts in another position;

Figs. 6, 7 and 8 are cross sections on the lines 6—6, 7—7 and 8—8 respectively of Fig. 4; and

Fig. 9 is a sectional view illustrating a slightly different form of the invention.

Referring to the drawings, 10 is an internal combustion engine having a carburetor 11 connected thereto. An exhaust pipe 12 is shown as extending along one side of the engine. Such an engine may be mounted in a motor vehicle and is usually arranged forward of a dash 13 which is in reach of the operator.

The carburetor 11 may comprise any desirable form of mixture device in which means are provided for varying the mixture. As shown there is a fuel nozzle 14, a main air intake 15, controlled by a butterfly valve 16, an auxiliary air intake 17 controlled by a valve 18, and a spring 19 adapted to yieldingly retain the valve 18 on its seat. A sleeve 20 operates on the stem of the valve 18 to adjust the tension of the spring 19. In Fig. 1 the parts are shown in normal position with the butterfly valve 16 wide open and the spring 19 set to its minimum position so that the valve 18 is very lightly seated. In this way the lighter loads will draw air through the main intake only but as the suction increases the valve 18 will be opened to increase the volume

of air and thus keep the proportions practically the same throughout the operation of the carburetor. The tension of the spring 19 may be increased to thereby lessen 5 the proportion of air and hence cause a richer mixture, by raising the sleeve 20. A cam 21, shown in dotted lines in Fig. 1 and in full lines in Fig. 2, is provided for this purpose. It is pivoted at 22 and is operated 10 by an arm 23. A second arm 24 has a pin and slot connection 25 with a rod 26 connecting with an arm 27 on the spring opened butterfly valve 16. A spring 28 is the means for retaining this valve 16 yielding 15 in its open position as it is shown in Fig. 1.

In Fig. 1 the above referred to parts of the carburetor are shown in their normal position or as set for running after the motor 20 has heated up. The valve 16 is wide open and the spring 19 is set at its minimum tension. In Fig. 2 the parts are in the other extreme position with the carburetor choked to its fullest extent so that practically no 25 air is admitted to it. Of course there is some air leakage past the valves, the valve 16 in particular being usually formed with a small leakage port, and in consequence a stream of liquid fuel is drawn from the 30 nozzle 14 by the action of the engine pistons as the engine is turned over by its starting motor. In this choked position of the parts of the carburetor the valve 16 abuts against the lower end of the stem of the valve 18, 35 as shown in Fig. 2, so that the latter valve is positively retained on its seat. It will be seen that by reason of the pin and slot connection 25 between the cam 21 and the valve 16 the cam moves throughout a greater part 40 of its range without changing the position of the valve 16. However, when the pin reaches the end of the slot the further movement of the cam 21 in tightening the spring 19 causes a quick closing of the choke valve 45 16.

Manually operated means are provided for moving the mixture varying means of the carburetor from one to another of its positions. This manually operated means, 50 as shown herein, comprises a rod 29 which extends through the dash 13 and has a handle 30 for the operator. The rod 29 is connected to a bell crank lever 31 pivoted on the engine as at 32 and having arms 33 and 34, the former of which is connected to the rod 29 and the latter of which is connected by a rod 35 to the arm 23 of the mechanism for varying the carburetor mixture. A device is provided for yieldingly 55 or frictionally retaining the rod 29 in its adjusted position, which device is sufficient to resist the tension of the carburetor spring 19 against the cam 21 tending to return the latter to its normal position. Such a retaining device is illustrated in Fig. 1 and is

indicated at 36 as mounted on the dash 13. It comprises a casting secured to the dash as shown and the rod passes through it and is engaged by a spring pressed ball 37 which enters serrations 38 in the rod. It will be 70 understood that the tension on the spring pressed ball 37 is just sufficient to retain the rod 29 in its set position from which it may be easily moved by the operator.

This means for moving the carburetor 75 mixture means from its normal position is adapted to be returned to normal position by a spring and dash pot device 39, shown in several of the figures. This device is shown in detail in Figs. 4 to 8 inclusive and 80 in the form illustrated it comprises a cylinder 40 having ears 41 by which it is secured to the exhaust pipe 12 as by bolts 42. The lower end of the cylinder is closed and at 85 its upper end it is provided with a cap 43 threaded onto it. A piston 44 operates in the cylinder and a piston rod 45 extends from the piston upwardly through the cap 43, the upper end of the rod 45 being formed with a flange 46. A coil spring 47 90 is arranged between the piston and the cap 43 to yieldingly press the piston, and with it the piston rod 45, towards the bottom of the cylinder. The piston 44 is formed with a series of openings or ports 48 there- 95 through and the cylinder is intended to contain oil or other fluid which may pass through the ports 48 from one part of the cylinder to the other as the piston moves in it. A valve 49 yieldingly pressed to its 100 seat by a spring 50 closes all of the ports 48 and thus prevents passage of the fluid from the lower to the upper part of the cylinder except through a leakage port 51 formed in the valve or elsewhere as desired. 105 The tension of the spring 50 is such that the valve 49 will readily open as the piston is moved upwardly to thus permit free passage of the fluid from the upper to the lower part of the cylinder. Thus there is 110 little or no retarding action of the piston as it moves upwardly. The cylinder 40 is also formed with a by-pass 52, the ports 53 and 54 of which are so arranged that the by-pass becomes operative and permits free 115 movement of the piston in either direction shortly before the piston reaches the upper end of its travel. The operation of the by-pass is shown particularly in Fig. 5. In 120 Fig. 4 the by-pass is inoperative because the piston has passed down over the port 53. The above described piston and dash pot device is connected to the means for operating the mixture varying device of the carburetor by means of an arm 55 which extends from the bell crank lever 31. The outer end of the arm 55 is in the form of a yoke 56 the parts of which pass on both sides of the piston rod 45 and operate 125 against the under side of the flange 46. 130

Thus when the rod 29 is moved by the operator towards the left in Fig. 1 the bell crank lever 31 is rocked on its pivot and the arm 55 moves upwardly and carries with it the piston rod 45 and the piston 44, against the action of the spring 47. In thus moving upwardly the piston 44 causes the valve 49 to open against its spring 50, to permit the free passage of the oil from the upper to the lower part of the cylinder. There is very little resistance to this movement. When the rod 29 is then released by the operator the spring 47 forces the piston downwardly and carries with it the arm 55 and thus rocks the bell crank lever 31. This movement, of course, returns the carburetor mixture device to normal position. If the oil in the cylinder 40 is thin this downward movement of the piston is comparatively rapid and the parts are at once returned to their normal setting. If, however, the oil in the cylinder is thick, as it is when it is cold, the downward movement of the piston is greatly retarded due to the fact that the oil must pass through the port 51 and the spring action therefore is sluggish and the parts return very slowly to their normal setting.

When the mechanism above described is used on an engine as shown the retarding action is very noticeable when the motor is cold but as the motor heats up the exhaust pipe transfers heat to the cylinder and thus the oil in the cylinder is warmed and becomes thin thus permitting the piston to return to its normal position. The piston can only be moved upwardly again by the operator, this action of the device being different from that of a thermostat.

It will be seen also that the arm 55 is so connected to the piston rod 45 that the arm may be returned to its normal position by pushing the rod 29 to the right in Fig. 1 without in any way operating the dash pot device. Thus the operator may wish to return the parts to normal immediately after the motor starts and without waiting for the spring and dash pot device to operate and this connection permits him to do so. In Fig. 5 the arm 55 is shown in full lines in its raised position and in dotted lines the arm 55 has been moved downwardly to normal position without carrying the piston rod 45 with it.

It will be understood further that the retaining device 36, above described, while it is sufficient to retain the parts in any desired position as against the action of the carburetor spring 19 on the cam 21, yet it is not sufficient to hold the rod 29 against the return-to-normal action of the spring 47.

The by-pass 52 above described is particularly related to the carburetor choke as will be seen in Figs. 1, 2 and 5. In Fig. 1

the carburetor mixture varying parts are in normal position and the piston 44 is at the lower end of its range of movement. In Fig. 2 the carburetor parts have been moved to their other extreme or choking position with the valves 16 and 18 tightly closed. In very cold weather it is sometimes necessary to choke the carburetor to this extent but it is very undesirable to let the motor run even for two or three seconds with the carburetor parts in that position because the motor will turn over very rapidly and draw in large quantities of raw gasoline unless the choke valve 16 is at once opened. It will be seen that in Fig. 2 the piston 44 has entirely over-traveled the port 53 and the by-pass 52 therefore is in full operation. This will permit the piston 44 to almost immediately retract as the rod 29 is released by the operator when the motor starts. But as soon as the piston has passed down over the port 53 the by-pass is cut off and the oil can then pass only through the small port 51. Of course, if the operator so desires, he can push the rod 29 towards the right in Fig. 1 immediately after the motor starts, and thus more quickly open the choke valve 16 while still retaining the valve 18 on its seat by reason of the nearly maximum compression of its spring 19. After the operator has left the rod 29 in that position, he need be no further concerned with the adjustment of the carburetor as it will be automatically taken care of by the spring and dash pot device, the mixture varying parts of the carburetor being returned to normal as the motor heats up. On the other hand, the operator may if he desires, return the mixture varying parts partly or wholly to normal position more rapidly than the spring and dash pot device will return them, should he desire a leaner mixture than the device is set to give. He cannot, however, leave the device in an intermediate position without having it automatically returned to normal and thus he cannot run a hot motor on a rich mixture without consciously holding the parts in abnormal position.

Referring to Fig. 9, a slightly modified form of spring and dash pot device is found. The cylinder 40 and by-pass, 52, as well as the piston 44 and spring 47 are the same. The piston rod 45^a, however, is drilled out and a rod 57 passes through the piston rod and connects by a cross bar 58 with the valve 49 so that the latter may be positively opened against its spring 50. The upper end of the piston rod 45^a has a slot 59 in which the end 56^a of the arm 55 operates. The slot 59 is slightly longer than the width of the head 56^a and the rod 57 extends into the slot in contact with the head 56^a. By this connection it will be seen that the piston rod 45^a may be moved upwardly by the

arm 55 as in the other construction, but the arm 55 cannot be moved downwardly without carrying the piston rod with it. To facilitate the manual downward movement 5 of the piston rod 45^a the valve 49 is opened by the movement of the rod 57 and this is accomplished by the head 56^a sliding in the slot 59 and operating on the end of the rod 57. Thus in Fig. 9 the arm 55 is in raised 10 position in full lines and in dotted lines the arm 55 has been moved downwardly so that the valve 49 has been opened thus permitting free passage of oil past the valve 59 and through the ports 48. Thus the operator may, as with the other construction, easily move the device in either direction and when he releases the rod 29 the spring 15 and dash pot device will act from then on to return the parts to normal, in accordance 20 with the heat of the motor.

It will be understood that various forms of the invention other than those described above may be used without departing from the spirit or scope of the invention.

Having thus described my invention, what I claim and desire to secure by Letters Patent is:

1. In an internal combustion engine, the combination of a mixture device therefor, 30 means for varying the mixture, a manually operated device to move said varying means from normal position, automatic means for returning said varying means to normal position upon manual release thereof, and 35 means governing the action of said automatic means.

2. In an internal combustion engine, the combination of a mixture device therefor, 40 means for varying the mixture, a device to move said varying means from normal position, automatic means for returning said varying means to normal position, and means for slowing down the action of said automatic means.

45 3. In an internal combustion engine, the combination of a mixture device therefor, means for varying the mixture, a device to move said varying means from normal position, automatic means for returning said 50 varying means to normal position, and a dash pot to retard the automatic return means.

55 4. In an internal combustion engine, the combination of a mixture device therefor, means for varying the mixture, a manually operated device to move said varying means from normal position, automatic means for returning said varying means to normal position upon manual release thereof, and 60 means dependent upon the heat of the engine for governing the action of said automatic means.

65 5. In an internal combustion engine, the combination of a mixture device therefor, means for varying the mixture, a device to

move said varying means from normal position, automatic means for returning said varying means to normal position, and means acting sluggishly on a cold engine and less so on a warm engine, for retarding 70 the automatic return means.

6. In an internal combustion engine, the combination with the cylinders and a carburetor adapted to supply mixture thereto, said carburetor having means for changing 75 the richness of the mixture, of a manually operated device for moving said mixture changing means from normal position, spring means for returning said mixture changing means to normal position, and retarding means for said spring means.

7. In an internal combustion engine, the combination with the cylinders and a carburetor adapted to supply mixture thereto, said carburetor having means for changing 85 the richness of the mixture, of a manually operated device for moving said mixture changing means from normal position, spring means for returning said mixture changing means to normal position, and a 90 dash pot adapted to retard the action of said spring means.

8. In an internal combustion engine, the combination with the cylinders and a carburetor adapted to supply mixture thereto, 95 said carburetor having means for changing the richness of the mixture, of a manually operated device for moving said mixture changing means from normal position, spring means for returning said mixture 100 changing means to normal position, and a dash pot mounted on the engine to receive heat therefrom, for retarding the return movement of the mixture changing means.

9. In an internal combustion engine, the 105 combination with a carburetor having a self-returning device for changing the mixture proportions, manually operated means for moving said device from normal position, a device for yieldingly retaining said means 110 in any set position, a spring adapted to overcome said retaining means and return the mixture device to normal position, and a dash pot for retarding the operation of said spring.

115 10. In an internal combustion engine, the combination with a carburetor having a self-returning device for changing the mixture proportions, manually operated 120 means for moving said device from normal position, a device for yieldingly retaining said means in any set position, a spring adapted to overcome said retaining means and return the mixture device to normal position, and means affected by the heat of 125 the engine, for retarding the action of said spring.

11. In an internal combustion engine, the combination with a carburetor having a self-returning device for changing the mixture 130

- proportions, manually operated means for moving said device from normal position, a device for yieldingly retaining said means in any set position, a spring adapted to over-
5 come said retaining means and return the mixture device to normal position, and an oil dash pot mounted adjacent the engine exhaust for retarding the action of said spring.
- 10 12. In an internal combustion engine, the combination with a carburetor having mixture controlling means, of a manually operated device for moving said means from and to normal position, and a spring device connected to said manually operated means to yieldingly return it to normal position without affecting the manual return of said means.
- 15 13. In an internal combustion engine, the combination with a carburetor having mixture controlling means, of a manually operated device for moving said means from and to normal position, and a spring and dash pot device to return said means to normal
20 position.
- 25 14. In an internal combustion engine, the combination with a carburetor having a mixture controlling device and a choker, and means for operating the mixture controlling device throughout a given range and for closing the choker near one end of the range of movement of said device, of a spring for yieldingly retaining said device in normal
- position, a dash pot connected to said means and adapted to retard the return action of
30 said spring throughout all the range of the movement of said device except the choker movement.
15. In an internal combustion engine, the combination with a carburetor, of means for controlling the carburetor comprising a spring return device, a cylinder, a piston in the cylinder, and a valve adapted to open in one direction to permit free movement of
35 the piston.
- 40 16. In an internal combustion engine, the combination with a carburetor, of means for controlling the carburetor comprising a spring return device, a cylinder, a piston in the cylinder, a valve adapted to open in one direction to permit free movement of the piston, and a by-pass to permit free movement of the piston in both directions throughout
45 a portion only of its full stroke.
- 50 17. In an internal combustion engine, the combination with a carburetor, of means for controlling the carburetor comprising a cylinder, a piston therein, a piston rod connected to the piston, a valve, an arm for moving the piston, and a connection from the arm to the valve whereby the latter may be manually opened to permit free movement of the piston.
- 55 In testimony whereof I affix my signature.

MILTON TIBBETTS.
